UNITED STATES PATENT OFFICE.

HEINRICH DREWELL, OF CHARLOTTENBURG, GERMANY, ASSIGNOR TO SCHNELLSETZMASCHINENGESELLSCHAFT MIT BESCHRÄNKTER HAFTUNG, OF BERLIN, GERMANY.

LINOTYPE-MACHINE.

No. 918,515.

Specification of Letters Patent. Patented April 20, 1909.

Application filed June 2, 1908. Serial No. 436,244.

To all whom it may concern:

Be it known that I, HEINRICH DREWELL, engineer, subject of the German Emperor, residing at Charlottenburg, Germany, have 5 invented new and useful Improvements in Linotype-Machines, of which the following is a specification.

The present invention relates to linotype machines, and an important object is to provide improved means for guiding the matrices in the same.

In linotype machines there is arranged a guide spring above the collecting star at the place where the matrices enter into the 15 assembling block from the guide channels of the collecting device. The purpose of this spring is to prevent the matrices, which fall at a high speed from the magazine, from flying too far and then not arriving at all, or not 20 in the correct position, in the assembling block. In the customary constructional forms this protecting spring is comparatively short and has a slightly curved shape. At its front end it has two short teeth which hold back the 25 upper ears of the matrices. The gap between these teeth is for allowing the space bars to pass freely into the collector or assembling block in case the spring should happen to be bent rather too far to the front. This known 30 arrangement is not sufficient, at high working speeds of the type setting machine, for preventing the matrices falling into confusion, being thrown out, or becoming jammed. Devices are also known, the object of which 35 is to guide the matrices in various different ways. The majority of these devices however, are neither intended nor are they suitable for rapid working, but are intended solely to protect the matrices as much as 40 possible.

In the ordinary operation of a linotype composing machine, when a composer operates the machine directly at the key-board, it is true that these defects are not so very 45 noticeable. For the composer works comparatively slowly; also he supervises the assembling of the matrices and at any moment can interfere in order to remedy a disturbance. But as soon as the composing 50 machine is operated automatically with the aid of a perforated register band, such disturbances occur very frequently. It then requires a comparatively long time in each case to remedy them.

Now an important object of the present

invention is to provide means which remedy these defects. This is obtained on the one hand by a suitably shaped guide spring for the matrices, and on the other hand by providing a second spring in addition. This 60 admits of the composing machine operating with great certainty even at the highest speeds.

In order that the invention may be clearly understood, reference is made to the accompanying drawing in which one embodiment is represented by way of example diagrammatically, and in which:

Figure 1 is a vertical transverse section through one part of the composing machine 70 showing the two springs which form the subject-matter of the invention, whereas Fig. 2 is a front elevation showing the lower portion of one of these two springs.

Referring to the drawing, 1 is the assembling block, and 2 the guide arranged in front of the latter. On the surface 3 of the latter there is a spring 9 on which the matrices slide down in order to arrive in the assembling block.

4 is a belt which runs over the wheel 5 and conveys the matrices to the guide 3; 6 are guide channels which receive the matrices from the magazine and bring them to the place where they are assembled or to the 85 belt 4. The collecting star 7 pushes the matrices which arrive below one after another into the assembling block 1. Above the inlet into the assembling block 1 is arranged the guide channel 8 through which 90 the space bars pass into the assembling block. Now between the guide 3 and the lower opening of the channel 8 there was formerly a spring which had at its front end two lateral, short teeth. According to the 95 present invention, instead of that spring there are two springs 10 and 11. Of these, particularly the outside spring 11 which is directly in the position of the older spring, differs from the latter in its special, peculiar 100 shape. Namely its front end is formed like a fork, the central portion of the spring being removed up to the dotted line 12 in Fig. 1. The lateral portions or prongs 13 and 14, which take the place of the short teeth 105 used formerly, are first bent slantwise upward and turn vertically down again at the front. The incision between these prongs or teeth permit the space bars to pass freely between them when falling out of the chan- 110

nel 8. These cannot therefore be stopped by the forwardly-bent end of the spring. On the inner side of spring 11 facing the guide 3 there is another slightly bent spring 10 which has no teeth at its bottom end. It is only so long that it extends to about the beginning of the bend in spring 11.

The entire device operates as follows:—
12 The front end of a matrix sliding down over
the collecting belt 4 first hits against the
spring 10, whereby the front end of the
matrix is diverted downward, without the
velocity of the matrix being appreciably di-
minished however. As soon as the matrix
15 hits against the collecting star at 16, it be-
gins to rise from its slanting, into the verti-
cal, position. But it can turn only as far as
this vertical position and is prevented from
turning farther by the teeth 13 and 14. It
20 is even impossible for the matrix to turn
farther than the vertical position when a
second matrix 17 hits behind the front
matrix 16. For firstly this blow can only
occur against the lower portion of the front
matrix, on account of the action of the
25 spring 10, and secondly the matrix 16, when
it is released by the teeth 13 and 14, is so
low down in the assembling block that the
matrix which is already in the assembling
30 block can no longer turn round its front edge.

It is true that by merely using the twice-
bent spring 11 instead of the kind of springs
employed hitherto, the capability of pro-
duction of linotype composing machines can
35 be considerably increased; the performance

which can be thus obtained, however, does not suffice for completely utilizing the ca-
pacity of production of the remaining parts
of this composing machine, and therefore
the simultaneous employment of both of the 40
new springs herein described for the purpose
of the present invention is absolutely nec-
essary.

What I claim as my invention and desire
to secure by Letters Patent is: 45

1. In a composing machine of the char-
acter described, the combination with a matrix
channel, of a guide spring mounted therein,
and a second guide spring on the former
spring, said second spring having a fork- 50
shaped front end with comparatively long,
downwardly bent prongs.

2. In a composing machine of the char-
acter described, the combination of a matrix
channel and a guide channel for the space 55
bars, a guide spring mounted in the machine,
said spring having its end extending for-
wardly under the space bar channel and
having its end turned downwardly beyond
said channel, said end being forked, the re- 60
cess formed by the fork extending rear-
wardly beyond the space bar channel.

In testimony whereof I have signed my
name to this specification in the presence of
two subscribing witnesses.

HEINRICH DREWELL.
